UNITED STATES PATENT OFFICE.

FRANZ A. BARTELMEZ, OF NEW YORK, N. Y.

PACKAGE.

SPECIFICATION forming part of Letters Patent No. 660,141, dated October 23, 1900.

Application filed April 12, 1900. Serial No. 12,553. (No model.)

To all whom it may concern:

- Be it known that I, FRANZ A. BARTELMEZ, a citizen of the United States, residing in the city, county, and State of New York, have invented certain new and useful Improvements in Packages, of which the following is a specification sufficient to enable others skilled in the art to which the invention appertains to make and use the same.
- 5 My invention relates to packages for containing manifold or carbon sheets for use in type-writing machines, the object being to afford a neat, compact, and substantial receptacle in which the said sheets may be conveniently and safely placed for transportation and storage without subjecting the same to pressure and from which they may be quickly and conveniently removed for use when desired.
- 10 The invention consists in a special form of box or package hereinafter shown and described specifically, in the combination with two protecting and stiffening sheets between which the carbon-manifolds are contained,
- 15 said protecting-stiffeners being readily inserted or withdrawn from the receptacle and performing the function of a slide or drawer by means of which the carbon-manifolds may be wholly or partially withdrawn from the package to admit of the removal of one or more of the carbon-sheets and again quickly and conveniently inserted in position within the receptacle without danger of derangement or rupture, as hereinafter set forth.
- 20 An incidental feature of my invention consists in the use of sliding stiffeners which are non-absorbent in character, so as to retard the drying out or deterioration of the manifold-paper between them.
- 25 In the accompanying drawings, Figure 1 is a plan of the blank from which my improved receptacle is formed. Fig. 2 is a view of the same, the parts being folded and secured together with the flap open and showing a portion of one of the sliding stiffeners. Fig. 3 is a longitudinal section of the package, upon an enlarged scale, the central portion being broken away and the flap being shown as closed. Fig. 4 is an isometrical perspective
- 30 of the package, showing the sliding stiffeners and manifold-paper partially withdrawn, the outer end of the upper sliding stiffener being shown as raised to give access to the sheet of carbon-paper to be used. Fig. 5 is a transverse section of the package and contents 55 upon an enlarged scale.
- 35 The blank B, of which the package P is formed, is shown extended in Fig. 1, the dotted lines b b indicating the lines at which the blank is folded. These lines may be 60 scribed or scored, if desired, in any convenient manner to facilitate the bending of the material and insure a correct alinement of the parts.
- 40 In forming the package the fold B' is first 65 bent over the main portion of the blank and the opposite fold B² is then bent over so as to overlap the edge of the fold B', in which position the two are secured together by any convenient or well-known expedient, as by the use of an adhesive agent or otherwise.
- 45 The end fold B³ is then bent over and secured in position in like manner, the flap B⁴ being then folded so as to overlap the edges b' b' of the folds B' B², but not secured thereto. 70 Thus the flap B⁴ may be turned back freely upon the lines b² b² to open the package and afford access to the contents thereof. In this connection it will be noticed that the edges b' b' of the folds B' B² are purposely 75 formed so as to converge toward each other centrally, thereby exposing and giving access to the sliding stiffeners S S and the carbon-sheets C when the flap B⁴ is thrown open. The V-shaped opening formed by the converging edges b' b' facilitates the grasping of the sliding stiffeners S by the fingers when it is desired to withdraw said sliding stiffeners for the purpose of extracting a carbon-sheet from between them. The folding lines 80 b b of the comparatively stiff blank are arranged so as to create a permanent well-defined internal space p of parallelepipedal form adapted to receive and accommodate the flexible sliding stiffeners S with the sheets 85 of carbon-manifolds between them without subjecting the same to pressure in any part, thereby maintaining the carbon-sheets in a comparatively free loose condition with relation to the stiffeners S and to each other, a 90 very important advantage when the sticky smudgy nature of the manifold-sheets is taken into consideration. The stiffeners, while relatively much stiffer than the carbon-sheets

which they are designed to protect and preserve in alinement, are still sufficiently elastic to admit of their being bent outward to give access to the carbon-sheets when the latter are partially withdrawn, as indicated in Fig. 4 of the drawings. These sliding stiffeners may be made of any desired material, as of comparatively stiff cardboard, &c., and they are preferably rendered non-absorbent for the purpose of more effectually protecting the carbon manifold-sheets between them and retarding the drying out or deterioration of said carbon-sheets.

The sliding stiffeners may be made of non-absorbent material having the required stiffness and flexibility, or may be treated in any convenient or well-known manner to render them non-absorbent.

What I claim as my invention, and desire to secure by Letters Patent, is—

1. A package for containing carbon manifold-sheets without subjecting the same to pressure, consisting of a blank B of comparatively-stiff material folded on the lines b, b, to create a space p, of parallelepipedal form, in combination with flexible sliding stiffeners S, S, fitting in said space p, and adapted to protect and preserve the alinement of car-

bon manifold-sheets placed between them, and to act in conjunction to facilitate the insertion or withdrawal of the same as set forth, said stiffeners S, S, having sufficient flexibility to admit of their being bent outward to give access to the carbon-manifolds when the latter are partially withdrawn from the package as herein described.

2. A package for containing carbon manifold-sheets without subjecting the same to pressure, consisting of a blank B, of comparatively-stiff material folded on the lines b, b, to create a space p, of parallelepipedal form, in combination with sliding stiffeners S, S, fitting in said space p, and adapted to protect and preserve the alinement of carbon manifold-sheets placed between them and to act in conjunction to facilitate the insertion or withdrawal of the same as set forth, said stiffeners S, S, being made non-absorbent for the purpose of retarding the drying out and deterioration of the carbon-manifolds as herein described.
